(57) **CLAIM**

The ornamental design for an angled ejection port for guns, as shown, and described.

DESCRIPTION

FIG. 1 is a left top side perspective view of an angled ejection port for guns showing our new design;

FIG. 2 is a right top side perspective view thereof;

FIG. 3 is a right side view thereof;

FIG. 4 is a left side view thereof; and,

FIG. 5 is a top view thereof.

The broken lines shown in each of the figures is for the purpose of illustrating and forms no part of the claimed design.
